ALARM

Curtis W. Keegin, Grosse Pointe, Mich., assignor
of one-half to Jay H. Gould, Detroit, Mich.

Application April 25, 1938, Serial No. 204,180

11 Claims. (Cl. 116—102)

This invention relates to alarms and refers more particularly to improvements in temperature responsive alarms especially adapted for sounding warnings of fire.

5 One object of my invention is to provide an alarm which will have improved and enlarged utility over prior fire alarms.

Another object is to provide an alarm, preferably of a readily portable nature, which may 10 be manufactured and sold at relatively low cost enabling use by a large number of people, thereby also enabling many to purchase a number of my alarms for location at several points in a home for example.

15 In carrying out the objects of my invention, I preferably incorporate my improvements in conjunction with an alarm clock of any suitable type such as ordinary commercial alarm clocks now sold in large quantity. I have provided 20 temperature responsive or thermostatic control means functioning with the alarm mechanism of an ordinary alarm clock, of either the electric or hand-wound type, for controlling the clock alarm.

25 In the interests of increasing the utility of my invention, I have provided an alarm of the character aforesaid so constructed and arranged that the alarm clock has all of its present functions and utility and in addition thereto a user of my 30 clock has the protective warning against fire hazard. Thus the alarm will be sounded when the surrounding temperature rises above a predetermined normal degree independently of the time setting of the alarm and independently of 35 the usual alarm control, viz., whether such control is set for "off" or "on."

It will be apparent that my invention has particular utility for domestic use. Since the ordinary alarm clock is readily portable and can be 40 located at a variety of points, a user of my clock can place the same most advantageously with respect to fire hazards and warning thereof during day and night. Furthermore, since my alarm 45 preferably has the further utility of indicating the time, the alarm has continuing utility in contrast with alarm devices which have utility only in the event of fire. This encourages the use of a number of my alarm devices throughout 50 a home in the interests of protection against loss of life and property.

Further objects and advantages of my invention reside in the novel combination and arrangement of parts more particularly hereinafter described 55 and claimed, reference being had to the accom-

panying drawings which illustrate the principles of my invention and in which:

Fig. 1 is a front perspective view of my alarm embodied in conjunction with a conventional electric alarm clock. 5

Fig. 2 is a front elevational view of my alarm, the dial and casing being removed to illustrate the clockwork and alarm mechanisms.

Fig. 2—A is a detail fragmentary side elevational view of a portion of the mechanism for 10 setting the clock hands.

Fig. 3 is a sectional plan view of the Fig. 2 mechanism taken as indicated by line 3—3 of Fig. 2.

Fig. 4 is a front sectional elevational view taken 15 as indicated by line 4—4 of Fig. 3.

Fig. 5 is a similar view taken as indicated by line 5—5 of Fig. 3.

Fig. 6 is a side elevational view of a portion of the Fig. 2 mechanism, illustrating my temperature responsive means. 20

Fig. 7 is a fragmentary perspective view further illustrating the Fig. 6 mechanism.

Fig. 8 is an enlarged view of a portion of the mechanism as seen in Fig. 3. 25

Fig. 9 is a generally similar view illustrating a modified form of my thermostatic control.

Fig. 10 is a view generally similar to Fig. 9 but illustrating a further modified arrangement of 30 thermostatic control.

Referring to the drawings, I have illustrated my invention in conjunction with an electric alarm clock of well known commercial type although I desire to point out that other types of clocks, electrically or manually wound, are 35 equally adaptable for use with my invention. Also, if desired, my invention may be employed without utilizing a clock mechanism although, as aforesaid, one important characteristic of my invention resides in my thermostatic control 40 means for conventional clocks of the alarm type.

The alarm clock A comprises an annular casting 15 having the usual front glass cover 16, a portion of which is broken away in Fig. 1 to indicate the dial 17 cooperating with the usual minute 45 and hour hands 18 and 19 respectively. The type of clock illustrated is the electric portable desk or table type having the casing support 20, a lead wire 21 having the electrical plug 22 for insertion in the usual socket for energizing the clock 50 motor. Other well known types of clocks are adapted for wall mounting, etc., as will be readily understood.

The clock mechanism is carried by a frame or chassis including a front plate 23 and rear plate 55

24 held in fixed spaced relationship by a plurality of main spacers 25. The driving prime mover is, in this instance, the electric synchronous motor B having the usual rotor 26 driving pinion 27 counterclockwise as viewed from the front.

The usual reduction train to the minute hand 18 consists of the following gears, viz., pinion 27 drives gear 28 fixed to shaft 29 which carries pinion 30 at its rear end. Pinion 30 drives 10 through reduction cluster gears 31, 32 and 33, 34. Cluster gears 33, 34 drive forwardly through shaft 35 to rotate gear 36 clockwise, the drive thence passing through idler 37 to the minute gear 38 which rotates the minute hand 18.

35 The usual reduction train to the hour hand 19 consists of the following gears, viz., gear 34 drives gear 39 on shaft 40 which extends forwardly to pinion 41 meshing with gear 42 which is disposed adjacent the rear of front plate 24. 20 The gear 42 drives through the usual friction connection generally indicated at 43, see Fig. 2—A, to the hand set pinion 44 rotatable by a shaft 45 and hand knob 46 for setting the hands 18 and 19 of the clock independently of the clockwork 25 drive in the conventional manner. Gear 44 meshes with gear 47 having pinion 48 engaging both the hour hand gear and the alarm trip gear 50.

For convenience of reference, all rotations unless otherwise stated will be with reference to a viewpoint looking at the clock front as in Figs. 1 and 2.

The usual alarm impulse mechanism or spring 35 at 51 urges gear 52 clockwise to drive pinion 53 and escapement wheel 54. The spring is maintained energized by a drive from the clockwork mechanism at gear 42 which drives cluster gears 55, 56, the latter meshing with spring winding gear 57. The usual spring clutch 58 allows the 40 gears to drive after the spring is fully wound up.

The alarm dial 59 is fixed to a shaft 60 extending rearwardly to knob 61 having counterclockwise rotation for setting the alarm according to the dial reading visible through a window 62 in 45 the main clock dial 17. The shaft 60 extends loosely through the alarm trip gear 50, this shaft having fixed thereto a disk-like body 68 having a trip finger 63. The trip gear 50 carries a trip collar 64 formed with a notch 65. Fixed at 66 50 to a plate 23 is a cantilever trip spring 67 which has a free end acting forwardly to urge gear 50 and its collar 64 toward finger 63. The gear 50 rotates clockwise from the driving clockwork mechanism, it being apparent that when notch 55 65 moves opposite the setting 63, the free end of spring 67 will snap outwardly from plate 23 causing outward movement of collar 64 as the notch engages the finger. This action is brought about since the collar 64 is hollow and receives the disk-like body portion 68 with the finger 63 entering notch 65 and limiting the outward movement of the spring 67 and gear 50. When the finger enters the notch the time alarm will sound provided the manual cut-off control for the alarm 60 impulse mechanism has been set for operation of the alarm as will be presently apparent. It will be understood that gear 50 maintains engagement with the wide-face gear 48 at all times.

The escapement wheel 54 rotates counterclockwise under control of an escapement 69 fixed to a rockshaft 70 supported between plates 23 and 24. Fixed to this rockshaft is a primary lever 71 having an end portion 72 engageable with a preset alarm control mechanism. Pivoted by a pin 75 73 to an intermediate portion of lever 71 is the

arm 74 of a secondary lever in the form of a belicrank 75 having its other arm 76 terminating in an alarm striker or hammer 77. Lever 75 is carried by a second rockshaft 78 and has its arm 74 terminating in a stop in the form of an outwardly bent finger 79 adapted for cooperation with the trip spring 67 to release the hammer 77 for vibration by spring 51 and escapement 69. A rear casing member 80 has an annular forwardly extending flange 81 partially enclosing the clockwork mechanism and provides a sounding device or gong for impact from hammer 77.

In order to preset the alarm for time operation or to permanently lock-out the alarm from operation by the time control, it is customary to provide a manual preset control mechanism of some type as for example a knob 82 carried by a shaft 83 axially slidably transversely of plates 23 and 24. This shaft carries an enlarged stop 84 having sloping sides 85, 86. When shaft 83 is pushed in or forwardly, the alarm is rendered inoperative by the time trip spring 67 because stop 84 is positioned so as to prevent vibration of lever portion 72. However, with shaft 83 pulled out or rearwardly, the alarm impulse mechanism between escapement 69 and hammer 77 is free to operate provided the time responsive tripping mechanism controlled by the trip finger 63 functions to release the alarm impulse mechanism and hammer 77.

Generally speaking, the foregoing details of parts are well known in the art and have been briefly referred to as illustrative of a typical environment for my invention. The general operation of the illustrated clockwork is also well known.

In carrying out the principles of my invention according to the embodiment thereof illustrated in Figs. 1 to 7, I have provided temperature responsive means arranged to function independently of the normal functioning of the clock mechanism so that the alarm will be sounded on predetermined temperature rise regardless of whether the manual cut-off control for the alarm impulse mechanism at knob 82 is in the "on" or "off" condition, and regardless of whether the time responsive alarm tripping mechanism controlled by trip finger 63 functions to release the alarm impulse mechanism and hammer 77.

I have provided a thermostatic element preferably in the form of bi-metal for causing the alarm to sound independently of the setting of the time responsive trip mechanism. In carrying out my invention, according to the illustrated embodiment thereof in Figs. 1 to 8, I form an element of the alarm impulse mechanism to operate as the thermostatic control preferably in cooperation with the trip spring 67. In this manner an operating part of the standard alarm mechanism is made to have several functions, viz., a function of temperature responsive trip control for the alarm impulse mechanism and also the normal functions of the part. As best seen in Figs. 6 to 8, the lever 75 is of thermostatic bi-metal material so constructed and arranged that when the temperature surrounding the clock rises above a predetermined normal or "safe" degree the outer end of lever portion 74 will rapidly deflect or bend so that the finger 79 will be moved rearwardly clear of the trip finger 67 which, in the conventional type of clock illustrated, is formed as a rearwardly bent portion of the trip spring 67 extending through an opening 88 to normally engage either the upper or lower face of the finger 79 to prevent operation of the

alarm impulse mechanism between the escapement 69 and hammer 71. If there is no manual cut-off control at 82 or if the latter is pulled rearwardly to release the lever portion 72 to freely vibrate, then the escapement 69 will immediately operate to vibrate hammer 71 against the gong 81 and sound a warning when said temperature rise causes lever 74 to deflect rearward face from trip finger 87.

For low cost manufacture the entire lever 76 including hammer 71 may be formed of the bimetal although it will be understood that the resulting deflection of lever 76 only slightly assists the desired thermostatic deflection of lever 74. If desired, levers 74 and 76 may be formed separately, only lever 74 being of thermostatic material or the arrangement of parts may be otherwise varied. The temperature responsive deflection of lever 76, when formed as in Fig. 8, will not interfere with hammer 71 striking the gong 81 as the linkage and escapement of the impulse mechanism is such that sufficient overtravel or clearance is provided to accommodate the slight change in the effective length of lever 76 when deflected by said temperature rise. The resulting movement of the hammer 71 is, for the most part, in the same general direction of movement as that of finger 79.

In order to accommodate the deflection of lever 74 without binding tendency at pivot 73, the lever 74 may have clearance at 89 (see Fig. 7) with pivot 73 and lever 74 is normally spaced sufficiently forwardly from lever 71 to accommodate the rearward deflection of finger 79.

When trip finger 63 enters notch 65 for sounding the alarm for normal functioning in response to the time setting 61, trip spring 67 bends or deflects forwardly to move its trip finger 87 free from finger 79 and the alarm will sound provided, of course, that the manual cut-off 82 has been previously pulled rearwardly so that stop 84 is clear of lever portion 72.

When knob 61 is then rotated counterclockwise, finger 63 engages the inclined face of notch 65 and restores spring 67 rearwardly to its fully loaded condition, the trip finger 87 thereupon springing rearwardly to catch the finger 79 of the thermostatic lever 74.

The alarm is normally shut off by pushing on the manual cut-off control knob 82 to cause lever portion 72 to engage stop 84 preferably at the inclined face 86 for reasons presently apparent. A detent cantilever spring 90 has an ear 91 loosely receiving shaft 83 and is fixed at 92 to plate 23. This spring 90 is, like element 89, a thermostatic element preferably bi-metal, and has an inverted V-shaped end portion 93 engageable with inclined face 85 to yieldingly hold shaft 83 in the forwardly pushed position. When knob 82 is pulled rearwardly, as in setting the alarm impulse mechanism for operation, stop 84 springs the element 90 and the end portion 93 then engages face 85 to yieldingly maintain the shaft 83 in its rearward position. The element 90 therefore has the function of an ordinary detent spring for shaft 83 and the further function of releasing the alarm mechanism regardless of the manual setting of knob 82.

Thus, if knob 82 is pushed forwardly and the temperature rises above the aforesaid predetermined normal degree, element 90 will rapidly swing downwardly free of stop 84 and, with thermostatic lever 74, simultaneously releasing trip finger 87 as aforesaid, the vibrating tendency of lever 71 will cause lever end portion 72 to act on

the sharply inclined face 86 to thereby move shaft 83 rearwardly sufficiently to allow full vibration of hammer 71 in sounding the alarm.

In the foregoing description I have, for convenience of identification, referred to parts moved "forwardly" or "rearwardly" with reference to the clock as viewed in Fig. 1 wherein the front is obviously at the clock face. The time responsive alarm trip mechanism primarily comprises trip finger 63, collar 64, spring 67 and finger 87, this mechanism further including the manual preset time control at knob 61. The alarm impulse mechanism is motivated by impulse spring 51 and comprises the escapement mechanism 54, 69 and vibratory levers 71, 75. The manual cut-off control for the alarm impulse mechanism comprises the knob 82 and parts associated with the functions of this knob. The foregoing mechanisms and controls may take a variety of forms within the broader aspects of my invention.

In order to efficiently effect operation of the thermostatic elements in response to the aforesaid temperature rise in the vicinity of my alarm device, the casing 15 is preferably provided with one or more apertures 94 to efficiently expose the thermostatic elements to the surrounding medium.

In the Fig. 9 modification the parts are identical in structure and function with those of the foregoing embodiment except as follows. In this instance the detent spring 90^a and securing ear 91^a are formed of ordinary steel spring stock. The rear plate 24^a is deflected rearwardly at 95 to accommodate rearward displacement of shaft 70^a under temperature responsive expansion of a thermostatic coiled element 96, preferably bimetal, which surrounds shaft 70^a and has one end fixed to plate 23 and the other end fixed to a collar 97. This collar is formed with a cam face 97^a for camming engagement with a cam face 97^b of a collar 97^c fixed with lever 71. The escapement 69^a is made wider than escapement 69 so as to maintain engagement with escapement wheel 54 when shaft 70^a is displaced rearwardly by the action of thermostatic element 96. A light spring 98 acts between plate 24^a and escapement 69^a to yieldingly maintain the parts in the Fig. 9 position and return the parts to this position after displacement by element 96.

The shaft 78^a is also preferably mounted for rearward displacement in plates 23, 24^a. While one thermostatic element will ordinarily be sufficient to effect operation of the alarm, in a manner presently more apparent, I prefer to also provide a second thermostatic element 99, similar to element 96, especially where detent spring 90^a is not a thermostatic element as at 90 in Fig. 8.

The thermostatic element 99 likewise has one end fixed to plate 23 and has its rear end fixed to a collar 100 formed with a cam face 100^a for camming engagement with a cam face 100^b of a collar 100^c fixed to lever 75^a for shifting shaft 78^a in opposition to a light return spring 101. In this embodiment lever 75^a is an ordinary non-thermostatic stamping in normal relatively close assembly at pivot 73^a with lever 71, and lever 75^a has portions 78^a, 74^a, 76^a and 77^a otherwise identical in structure and function with the corresponding portions 78, 74, 76 and 77 of the aforesaid lever 75.

With shaft 83 in pushed-in Fig. 9 cut-off position, elements 96 and 99 (where they are both employed) will expand in response to the aforesaid predetermined temperature rise to respectively cause counterclockwise rotation of collars 97 and 75

100 for camming collars 97^a and 100^a to rearwardly displace shafts 70^a and 78^a together with levers 71 and 75^a as a unit assembly, sufficiently to move finger 79^a clear of the trip finger 87 to thereby cause operation of the alarm impulse mechanism to sound the alarm. Preferably, the arrangement is such that expansion of elements 96 and 99 will force stop 84 and shaft 83 rearwardly to spring the detent 98^a until the V-end 93^a 10 engages inclined face 96 whereupon the spring 93^a will force shaft 83 rearwardly. The elements 96 and 99 cooperate to give a balanced displacement to the impulse assembly during this alarm releasing action. Unless elements 96 and 99 15 are called on to expand, the normal clock and time responsive functions may take place just as in a conventional alarm clock but the thermostatic device is always ready to sound the alarm regardless of the setting at knobs 81 and 82.

20 The thermostatic elements 96 and 99 are free to contract without interfering with the normal operation of levers 71 and 75^a to sound the alarm in response to operation of the time control. When these thermostatic elements expand the 25 cam faces are disengaged, the shafts 70^a and 78^a being shifted rearwardly, so that the levers may vibrate without interference with cams 97^a and 100^a. Under normal temperature conditions sufficient clearance is provided between the pairs of 30 cam faces to allow free vibration of the levers to sound the alarm by the time control mechanism.

In Fig. 10 I have illustrated an arrangement for shifting the shafts 70^a and 78^a as in Fig. 9 but instead of a coil type of thermostatic element (as at 96 and 99 in Fig. 9), I have provided a bi-metal flat element 102 supported at 103 to plate 23 and having its opposite ends respectively adapted to engage pins 104 and 105 of shafts 70^a and 78^a. Under predetermined temperature rise, 40 as aforesaid, element 102 will flex and displace these shafts rearwardly together with the lever assembly just as in Fig. 9 and with identical results as will be readily understood.

I do not limit my invention in its broader aspects to the particular form and arrangement of parts shown and described for purposes of illustrating the principles of my invention since many changes and modifications will be readily apparent from my teachings.

50 I claim:

1. In a device of the character described, an alarm, vibratory mechanism adapted to be tripped for operating said alarm, and a time controlled trip element for tripping said alarm operating mechanism, said mechanism comprising a vibratory thermo-active lever, spring means urging vibration of said lever, and means for pivotally supporting said lever for normal engagement thereof with said trip element to prevent vibration thereof and for accommodating movement thereof in response to predetermined temperature variation out of engagement with said trip element to permit vibration of said lever by said spring means for sounding said alarm.

65 2. In a device of the character described, an alarm, mechanism adapted to be tripped for operating said alarm, and a time controlled trip element for tripping said alarm operating mechanism, said mechanism including a thermo-active

70 hammer element having a stop portion thereof normally engaging said trip element and deflecting in response to predetermined temperature variation for tripping said alarm operating mechanism.

75 3. In a device of the character described, an

alarm, vibratory mechanism adapted to be tripped for operating said alarm, a time controlled trip element for tripping said alarm operating mechanism, said mechanism comprising a vibratory stop lever, spring means urging vibration of said lever, means for pivotally supporting said lever for normal engagement thereof with said trip element to prevent vibration thereof and for accommodating shifting movement thereof out of engagement with said trip element to permit vibration of said lever by said spring means for sounding said alarm, and thermo-active means operable in response to predetermined temperature variation for shifting said lever as aforesaid.

4. In a device of the character described, an alarm, mechanism adapted to be tripped for operating said alarm, a time controlled trip element for tripping said alarm operating mechanism, said mechanism including a vibratory hammer element having a hammer portion thereof adapted to strike the alarm and a stop portion thereof normally engaging said trip element, and thermostatic means operating to displace said hammer element to an operable position thereof wherein said stop portion is free from engagement with said trip element for tripping said alarm operating mechanism.

5. In a device of the character described, an alarm, mechanism adapted to be tripped for operating said alarm, a time controlled trip element for tripping said alarm operating mechanism, said mechanism including a stop normally engaging said trip element, manually operable means shiftable from a first position to a second position for preventing operation of said alarm operating mechanism, and means operating in response to predetermined temperature variation for displacing said stop from engagement with said trip element to trip said alarm operating mechanism and for shifting said manually operable means from said second position to said first position.

6. In a device of the character described, an alarm, a time controlled trip element, and vibratory mechanism adapted to be tripped for operating said alarm, said mechanism including a vibratory stop normally engaging said trip element to check vibration thereof and adapted for displacement free from said trip element in response to predetermined temperature variation, spring means urging alarm-operating vibration of said stop, and means mounting said stop for vibratory movement in a predetermined path by said spring means, said mounting means accommodating displacement of said stop generally transversely of said path to free said stop from said trip element as aforesaid.

7. In a device of the character described, an alarm, alarm operating mechanism including a vibratory control element, arresting means normally interposed in the path of said element to prevent vibration thereof, thermo-active means for moving said element free of said arresting means to release said mechanism to operate said alarm, and means for mounting said element to accommodate vibration of said element and movement of said element free of said arresting means aforesaid.

8. In a device of the character described, an alarm, alarm operating mechanism including a vibratory thermo-active lever, and vibration arresting means normally interposed in the path of said lever, said lever distorting in response to predetermined temperature rise free from said

- arresting means thereby releasing said mechanism to operate said alarm.
9. In a device of the character described, an alarm, alarm operating mechanism including a system of pivotally jointed vibratory levers, vibration arresting means normally interposed in the path of one of said levers, and thermostatic means for displacing said levers for vibration free from said arresting means.
10. 10. In a device of the character described, an alarm, alarm operating mechanism including a thermo-active hammer, arresting means for said mechanism, said hammer deflecting in response

to predetermined temperature variation to free said mechanism from said arresting means.

11. In an alarm clock having a clockwork driven time indicator, a trip operable synchronously with said time indicator, and alarm mechanism including a vibratory stop normally engaged with said trip, spring means urging vibration of said stop, and means mounting said stop for displacement thereof out of engagement with said trip in response to predetermined temperature variation.

CURTIS W. KEEGIN.
